THROWABLE-CATCHABLE TACKLING BAG
John J. Cizuk, 1407 N. Main St., Aveca, Pa.
Filed Oct. 27, 1961, Ser. No. 148,069
4 Claims. (Cl. 273—55)

This invention relates to football tackling bags and more particularly to a portable, scaffoldless tackling bag.

Heretofore, various types of scaffoldless football blocking bags have been proposed for use as false defensive men against which offensive football plays are rehearsed. However, such bags do not lend themselves for use as portable tackling bags due to their excessive weight. Furthermore, such bags are generally characterized by lack of rigidity and, accordingly, they tend to bend or become displaced about a vertical axis upon impact.

An object of the invention is to provide an improved portable, scaffoldless tackling bag for developing contact desire, left and right shoulder tackling, and defensive aggressiveness.

Another object of the invention is to provide an improved portable, scaffoldless tackling bag designed for use as a medicine ball in developing muscles of the abdomen, arms, legs, back, neck and shoulders.

Yet another object of the invention is to provide an improved portable, scaffoldless football tackling bag constructed and arranged, whereby the weight of the bag can be readily changed to accommodate it to the age and/or strength of the users.

Still another object of the invention is to provide an improved portable, scaffoldless football tackling bag having a reinforcing member incorporated therein, adapted to maintain the bag substantially rigid, so as to prevent it from bending or becoming displaced with respect to its axis of symmetry.

A still further object of the invention is to provide an improved portable, scaffoldless football tackling bag wherein the filling material thereof comprises a combination of specifically different materials of different specific gravities, distributed evenly within the bag, the heaviest material being confined to the central axial portion of the bag.

Yet a still further object of the invention is to provide an improved portable, scaffoldless football tackling bag having a symmetrical shaped body portion, and top and bottom closure members, the central portion of the body of the bag being of less diameter than the end closures, and gradually tapered from the center to the top, and from the center to the bottom, whereby the filled bag is of the general shape of a hyperboloid of revolution.

With these and other objects in view, which may be incident to my improvements, the invention consists in the parts and combinations to be hereinafter set forth and claimed, with the understanding that the several necessary elements comprising my invention, may be varied in construction, proportions and arrangements, without departing from the spirit and scope of the appended claims.

In order to make my invention more clearly understood, I have shown in the accompanying drawings means for carrying the same into practical effect, without limiting the improvements in their useful application to the particular constructions which, for the purpose of explanation, have been made the subject of illustration.

In the drawings:

FIGURE 1 is a perspective view of the improved scaffoldless tackling bag;

FIG. 2 is a sectional view taken along line 2—2 of FIG. 1;

FIG. 3 is a top plan view of the tackling bag shown in FIG. 1;

2

FIG. 4 is a sectional view taken along line 4—4 of FIG. 2;

FIG. 5 is a sectional view of a modification of the tackling bag; and

FIG. 6 is a sectional view taken along line 6—6 of FIG. 5.

Referring to the drawings, and more particularly to FIGS. 1—4, the tackling bag comprises a body portion 1, formed from heavy canvas or other suitable material, having top and bottom closure members 2 and 3, respectively, stitched or otherwise secured to the ends 2' and 3' of the body portion as at 4, the top closure member being provided with an opening 5 for the introduction of suitable filling material 6 and a reinforcing member 7, as will be described more fully hereinafter. The top closure 2 is further provided with an inner flap 8 adapted to fit over the opening 5, and with lacing 9 to close the opening over the flap. As will be seen in FIG. 2, the body portion of the bag is of gradually increasing diameter from its central or medial section 10 in the direction of the bag ends, being of greatest diameter in the vicinity of the top and bottom portions 11 and 12, respectively, and of gradually decreasing diameter from said portions to the ends 2' and 3' of the bag body, so that the filled bag has the general shape of a modified hyperboloid of revolution.

The filling material 6 comprises a mixture of materials of different specific gravities distributed uniformly within the bag. The materials which have been found to be well adapted for use as a filler are cotton and felt wastes, sawdust and foam rubber. While these materials, when mixed in proper proportions and packed in the bag, provide a certain degree of rigidity, it is desirable that the bag be sufficiently rigid to prevent bending under impact, and in accordance with the present invention, bending of the bag under impact is prevented by means of a reinforcing member positioned within the bag, concentric with the longitudinal axis thereof.

In addition to the provision of reinforcing means, it is also desirable that the bag be constructed and arranged so that its weight can be varied to accommodate it to a particular age group, or to the strength of the user. In accordance with the present invention, weight variation of the bag is accomplished by incorporating a predetermined quantity of a relatively heavy material in the reinforcing member. In other words, the reinforcing member performs a double function, namely, it increases the impact resistance of the bag, and it also serves as a carrier of the relatively heavy weighting material, the volume of which may be readily changed so as to vary the weight of the bag, as desired.

Referring to FIG. 2, the reinforcing member comprises a tube 13, positioned centrally of the bag concentric with the longitudinal axis 14 thereof, the ends 15 and 16 of the tube being spaced from the ends of the bag 2 and 3, respectively. The bag is adapted to be selectively weighted by introducing a predetermined volume of sand 17 into the tube, the sand being equally distributed above and below the traverse axis of the tube, as shown. The weight variation may be accomplished in any suitable manner. For example, a plurality of tubes, each containing a different quantity of sand may be provided, or sand may be added to or removed from the tube in situ.

In the modification shown in FIGS. 5 and 6, the reinforcing member comprises a wooden bar 18 of rectangular cross section, having a plurality of longitudinally spaced openings 19 adapted to receive lead pellets 20, for varying the weight of the bag. It will thus be seen that in lieu of using sand, as described in connection with the arrangement shown in FIG. 2, the weight of the bag may be varied by changing the number of lead pellets carried by the wooden bar.

Instead of using sand or lead pellets, as above de-

scribed, the weight of the bag may be varied by using suitable amounts of a relatively heavy material as one of the filler components. For example, it has been found that nylon and silk waste may be used with or substituted for the cotton waste to vary the weight of the bags. Although the body portion 1 of the bag shown in FIGS. 3, 4 and 6 is formed from a half pattern, that is to say, from two sections of canvas material, it will be understood that it can be formed from any desired number of sections.

The improved scaffoldless football bag of the present invention is intended to be used as a moving target and, accordingly, in tackling practice, it is transferred from one player to another in a certain sequence, depending upon the pattern in which the players are lined up. In one method, the tacklers line up in tandem, approximately fifteen yards apart; one of the players, designated as the "starter," is positioned in line with the tacklers, and upon a given signal, moves forward in the direction of the approaching tackler, with the bag supported on his right shoulder, and drops the bag on the right shoulder of the oncoming tackler in such fashion that the central or medial section 10 of the bag is in contact with the shoulder. As the bag hits his shoulder the tackler wraps both arms around the bag and positions it so that his left hand is underneath the bag and the right hand is in back of the bag, preparatory to dropping it on the right shoulder of the next approaching tackler. This procedure is repeated and is gradually speeded up as the players become more proficient, so that the dropping action of the bag develops into a push, shove or throw of the bag. The above described use of the bag is for right shoulder tackling. The same procedure is followed for left shoulder tackling, except that the bag is carried on the left shoulder with the right hand underneath and the left hand in back of the bag.

In right shoulder tackling, at the time of impact, the tackler should have his eyes on the target, trunk bent, feet spaced apart with left foot trailing for a brace. In left shoulder tackling the tackler's stance will be the same as for right shoulder tackling, except that the right foot will be trailing for a brace.

The improved tackling bag of the present invention develops contact desire, right and left shoulder tackling, defensive aggressiveness, and the muscles of the abdomen, arms, legs, back, neck and shoulders; it is economical in construction and use, since scaffolds or like supports for hanging-type tackling dummies are not required; it is adapted for all year use as a medicine bag in regular gymnasium classes, without helmets or shoulder pads; and the bag weight may be varied to suit the age and strength of the user, from high school through college, and professional football.

While I have shown and described the preferred embodiment of my invention, I wish it to be understood that I do not confine myself to the precise details of construction herein set forth by way of illustration, as it is apparent that many changes and variations may be made herein, by those skilled in the art, without departing from the spirit of the invention or exceeding the scope of the appended claims.

I claim:

1. A portable scaffoldless football tackling bag comprising a symmetrical shaped body member of circular cross-section having a central portion of less diameter than the ends of the bag and gradually tapered from said central portion in the direction of the bag ends, a closure member at each end of the bag, one of the closures having an opening for the introduction of filling materials, means centrally positioned within the bag concentric with the longitudinal axis thereof for reinforcing the bag against bending with respect to its axes of symmetry upon impact, said reinforcing means being spaced from the ends of the bag, an opening formed in the reinforcing means, and a selected volume of a relatively heavy material positioned within the opening, whereby the weight of the bag may be varied.
2. A portable scaffoldless football tackling bag in accordance with claim 1, wherein the means for reinforcing the bag comprises a tubular member having a selected volume of sand therein equally distributed above and below the transverse axis of the bag, the ends of the tube being closed by the bag filling materials.
3. A portable scaffoldless football tackling bag in accordance with claim 1, wherein the means for reinforcing the bag comprises a wooden bar having a plurality of longitudinally spaced openings equally distributed above and below the transverse axis of the bag, each of a selected number of the openings having a lead pellet positioned therein.
4. A portable scaffoldless football tackling bag comprising a symmetrical shaped body member of circular cross-section having a medial portion of less diameter than the ends of the bag and gradually tapered from the medial portion in the direction of the bag ends, a closure member at each end of the bag, one of said closures having an opening for the introduction of filling materials, filling materials of different specific gravity distributed uniformly within the bag, said filling materials comprising cotton, felt, nylon and silk wastes, sawdust and foam rubber, means centrally positioned within the bag concentric with the longitudinal axis thereof for reinforcing the bag against bending with respect to its axes of symmetry when the bag is dropped so that the medial portion thereof contacts the shoulder of a tackler, said reinforcing means being spaced from the ends of the bag, an opening formed in the reinforcing means, and a selected volume of a relatively heavy material positioned within the opening, whereby the weight of the bag may be varied.
